UNITED STATES PATENT OFFICE.

OLIVER H. GENTRY, OF OPELOUSAS, LOUISIANA.

SWINGING TREADLE.

SPECIFICATION forming part of Letters Patent No. 380,029, dated March 27, 1888.

Application filed December 2, 1887. Serial No. 256,823. (No model.)

To all whom it may concern:

Be it known that I, OLIVER H. GENTRY, a citizen of the United States, residing at Opelousas, in the parish of St. Landry and State of Louisiana, have invented certain new and useful Improvements in Swinging Treadles; and I do hereby declare the following to be a full, clear, and exact description of the invention, such as will enable others skilled in the art to which it appertains to make and use the same.

My invention relates to certain new and useful improvements in swinging treadles for sewing-machines or other mechanism requiring power.

It consists of a swinging lever adjustably connected to one or more swinging arms, that are in turn connected to a crank-arm of a revolving shaft or to a crank-pin on drive-wheel, or connected in any other suitable manner to mechanism to which it is desirable to impart motion.

The object of my invention is to impart motion to machines by means of a swinging foot-lever, one or more swinging arms, and suitable connections. I attain this object by means of the peculiar construction and arrangement of the various parts of my device, which will be more fully pointed out and described in the specification and claim, reference being had to the drawings accompanying this application and forming part of the same, in which—

Figure 1 is a view of my invention taken from the end of the sewing-machine. Fig. 2 is a front elevation, and Figs. 3 and 4 are detail views.

Similar letters refer to like parts throughout the drawings.

Referring to the drawings, A represents a sewing-machine frame, and B the bed or table. C represents the drive-wheel, and D the belt which connects with sewing-machine. (Not shown.) Metal plates E and E' are formed with inwardly-inclined end projections, a, adapted to fit tightly the edges of table B. Their opposite ends are formed with right-angular projecting lugs b, having perforations b', through which is passed a screw-bolt, c, and by means of which said plates are drawn tightly against the edges of table B, and are thus held

rigidly in place to the under face of said table. Near the end of plate E' a projecting ear or lug, d, is secured to its under face. Said lug is provided with a perforation, d', to receive pivot-bolt e. A swing-arm, F, is pivoted to lug d by bolt e and projects downward, and its lower end is perforated to receive bolt f. The upper portion of said arm is provided with a slot, g, adapted to receive a set-screw bolt, h. The lower end of arm F is pivoted to one end of pitman-rod G, and the opposite end of said rod G is perforated to receive crank-pin i, which is formed on crank-arm H, that is secured to shaft H', on which is secured drive-wheel C.

Plate E is formed with a dovetail-shaped slot, j, extending inward from its outer end, said slot being adapted to receive and hold loosely an ear-piece, k, which is formed with an extension, k', having a perforation to receive a thumb-screw bolt, k'', by means of which said ear-piece may be held at any desired position within the slot j. A perforation is formed in the ear-piece k, and a bolt, l, is inserted, to which the lever I is connected at one end, and the opposite end is provided with a foot-piece, J.

The upper end of lever I is slotted to receive set-screw m, to which is pivoted one end of the connecting-rod K, and the opposite end of said rod is perforated to receive screw-bolt h. The center of said connecting-rod K is formed with holes n and made to lap over, and is held by set-screw o, that passes through said holes when they register, the purpose being to lengthen or shorten said rod K when desired to conform to the change of the position of the ear k, holding the end of lever I, as shown in Fig. 1. A similar construction is used when two levers are connected to the ears k, as shown in Fig. 2, the foot-piece J extending across and joining the lower end of each of said levers.

In the detail view, Fig. 3, the inclined groove or slot j is shown, and Fig. 4 represents the beveled edges of the ear-piece k. This construction herein described, though shown and described as attached to a sewing-machine, it is readily understood, may be adapted to use on any machine or apparatus requiring such power to operate.

The operation of my device is obvious and needs no description.

Having thus described my invention, what I claim, and desire to secure by Letters Patent, 5 is—

A swinging treadle consisting of a slotted lever pivoted to a horizontally-adjustable lug, a slotted swing-arm pivoted to a rigid lug, said lever and arm connected at their slotted portions by an adjustable rod, a connecting-rod

pivoted at one end to the free end of said swing-arm and its opposite end to a crank-pin, and a foot-board on the free end of said lever, substantially as set forth.

In testimony whereof I affix my signature in 15 presence of two witnesses.

OLIVER H. GENTRY.
